UNITED STATES PATENT OFFICE

1,924,023

ADJUSTABLE WRENCH

August E. Carlberg, Worcester, Mass.

Application January 8, 1932. Serial No. 585,542

3 Claims. (Cl. 81—53)

The present invention relates to adjustable wrenches or tool holders and particularly to adjustable tool holders in which the angularity of the wrench head or tool head relative to the handle of the tool may be adjusted.

In prior devices of this character in which the head was angularly adjustable, the adjustable feature involved a complicated system of lever connections by which to procure the desired angular adjustment, said adjustment being effective through a small angle by rotation of a thumb screw or other suitable slow acting mechanism which rendered the construction cumbersome in use and resulted in a complicated and expensive construction. The utility of a tool of this character resides in its range of adjustability as well as its rapid and easy adjustment to any desired position. Accordingly, the principal object of the present invention is to provide a quick acting adjusting mechanism of simple construction, by means of which to procure adjustment of the tool head relative to the handle of the tool. According to the present invention, the tool head is pivotally mounted on the handle and is supported in desired position by a connecting member which is movably connected to said head and which is slidable relative to the handle, a locking means holding said connecting member against movement on said handle in any adjusted position.

A further feature of the invention resides in the provision of a wrench which will permit turning movement of the tool head on one end without swinging movement of the handle so that a nut or bolt in an inaccessible place may be engaged by the tool head and turned while the handle remains substantially in one position. In accordance with this feature of the invention, a tool head on one end of the handle is connected through links to a tool head mounted on the opposite end of said handle in such a manner that swinging movement of the tool head on one end of the handle will procure positive turning movement of the tool head on the opposite end.

The above and further objects and advantages of the invention will appear from the following detailed description taken in connection with the accompanying drawings in which:

Fig. 1 is a plan view of a tool embodying the invention, showing the tool head in one extreme position.

Fig. 2 is a rear view of the tool in Fig. 1.

Fig. 3 is a plan view of the tool of Fig. 1, showing the tool head in the other extreme position.

Fig. 4 is a plan view of a modified tool embodying the invention, the tool heads being in one extreme position.

Fig. 5 is a rear view of the tool of Fig. 4.

Fig. 6 is a plan view of the tool of Fig. 4, showing the tool heads in the other extreme position.

Fig. 7 is a plan view of a tool embodying a further modification of the invention.

Like reference characters refer to like parts in the different figures.

Referring to Figs. 1, 2 and 3, the invention is embodied in a wrench construction having a handle 1, one end of which is provided with a hand grip 2. The handle, from a point adjacent the grip 2 is slotted to form spaced parallel arms 3 and 4 between which the wrench head 5 is pivotally mounted, adjacent the outer ends of said arms, a pin 6, extending through the ends of said arms, providing a pivotal support for said head 5. The wrench head 5 which is cut out to provide a recess 7 for engagement with a nut or the head of a bolt, has a slot 8 therein in which the outer end of a connecting member 9 is mounted, a pin 10 in the wrench head, forming a pivotal support for said member 9, the slot 8 being arranged to permit rocking movement of the connecting member 9 relative to the head 5. The end of the connecting member 9 remote from the pin 10 extends into the space between the handle arms 3 and 4 and is provided with a pin 11 which projects through aligned longitudinal slots 12 in the arms 3 and 4, whereby the movement of the inner end of the connecting member 9 is limited to longitudinal movement along said handle 1.

A pawl 13 which is pivotally mounted on opposite ends of the pin 11 is provided with a flat inner surface 14 which is arranged to engage with any one of a set of ratchet teeth 15 formed in aligned edges of the arms 3 and 4. The angularity of the surface 14 is such that when the ratchet 13 is swung into engagement with any of the ratchet teeth 15, as shown in Fig. 1, or in Fig. 3, the wrench head 5 is held against turning movement. The head 5 is adjustable in any one of the several positions corresponding to the separate surfaces of the ratchet teeth 15 to vary the angularity of the head relative to the handle, thereby making it possible to engage a bolt or nut at different angles. It will be apparent that the swinging movements of the wrench head 5 are limited by the length of the slots 12, so that the head cannot be swung beyond desired limits; at the same time the angular position of the wrench head may be readily varied between these limits by swinging the pawl out of engagement with the ratchet teeth and then rocking the wrench head relative to said handle.

Referring now to Figs. 4, 5 and 6, the invention may be incorporated in a double-ended wrench of the S-wrench type. In this construction, the handle 17 comprises spaced parallel arms 18 and 20 connected at opposite ends by pins 21 and 22, and wrench heads 23 and 24 are pivotally mounted on said pins 21 and 22 respectively, between said spaced arms. The head 23, which is provided

with a recess 25 for engagement with a nut or the like, has a slot 26 therein to receive the end of a connecting member 27 which extends into said slot and is pivotally secured to the head 23 by a pin 28. The opposite end of the connecting member 27 extends between the arms 18 and 20 and carries a pin 29 which extends through aligned slots 30 extending longitudinally of said arms 18 and 20 substantially midway between the ends thereof. 5 The ends of said pin 29 provide pivotal supports for a pawl member 31 which functions, in cooperation with ratchet teeth 32 and 33 formed in aligned edges of arms 18 and 20 on opposite sides of pin 29, to hold the wrench head 23 in different 10 positions in the same manner disclosed with reference to the pawl 13 and ratchet teeth 15.

The other wrench head 24 is pivotally mounted on the stud 22 which connects the arms 18 and 20 at the end of the handle 17 remote from the head 23, said head 24 being positioned on said pin between said arms. As in the case of the head 23, the head 24 has a recess 34 for engagement with a nut or the like, and is provided with slot 35 which receives one end of a connecting member 36, the latter being pivotally secured in said slot by a pin 37 mounted in said head. The end of the connecting member 36 remote from the pin 37 is pivotally mounted on the pin 29 in the end of the connecting member 27 so that the single pin 29, and the single pawl 31 in connection with the ratchet teeth 32 and 33 operate to control the setting of both wrench heads 23 and 24.

The surface 38 of the pawl 31, in the full line position of said pawl in Fig. 4, operates to hold the wrench head 23 against counterclockwise rotation on the pin 21 and the wrench head 24 against clockwise rotation on the pin 22 by engagement of the surface 38 with the surface of one of the teeth 32. In the same manner when the pawl 31 is swung to the dotted line position, Fig. 4, the wrench head 23 is held against turning movement in the opposite or clockwise direction, and the head 24 is held against turning counterclockwise. However, with the pawl in this dotted line position, the wrench head 24 may be rotated clockwise, the pawl sliding over the teeth of the ratchet teeth 33 for engagement with the right hand surface of any of the teeth 33 to hold the head 24 against counterclockwise rotation in any one of the several adjusted positions as determined by the surfaces of the ratchet teeth 33. Similarly, the wrench head 23, with the pawl in the dotted line position of Fig. 4, may be turned counterclockwise to adjust said head to any one of the several different positions.

When the pawl 31 is moved to disengage the surface 38 from any of the ratchet teeth, rocking movement of the head 24 procures an opposite rocking movement of the head 23 without substantial movement of the handle 17. In this manner, when the head 23 is placed in engagement with a nut or with the head of a bolt, any angular movement of the free head 24 will impart to the engaged head 23 a correspondingly angular movement, thereby turning the nut or bolt with which the head 23 is engaged, although the handle 17 has remained substantially stationary. By this construction, nuts or bolts which are inaccessible to the ordinary type of wrench may be reached and turned.

In the modification of Fig. 7, the handle 1a has the grip portion 2a mounted on one end

thereof and carried on the opposite end a short socket wrench head or tool head 40 pivotally connected to the handle 1a by a stud 6a. A connecting member 9a is pivotally connected by a stud 10a to the wrench head 40 at one end, 80 the other end of said connecting member carrying a pin 11a which engages in a slot 12a extending longitudinally of the handle 1a. A pawl 13a is pivotally mounted on the ends of the pin 11a and is provided with a surface 14a which is arranged to engage selectively with ratchet teeth 15a formed on the rearward edge of the handle 1a. The tool head 40 which is arranged to receive a socket wrench 41 and to support the same removably thereon is adjustable to several angular positions relative to the handle 1a by rotation of said wrench head about the pin 6a, the pawl 13a holding said head in adjusted position in the manner above set out with reference to pawl 13. It will be noted that the head 40 is adjustable through an angle of substantially 90° and is held in adjusted position against movement in either direction.

From the foregoing, it will be apparent that the present invention provides a tool having a work-engaging head mounted thereon which may be set in a number of different angular positions relative to the tool handle. The tool is also arranged to permit a work-engaging head to be turned relative to said handle from a point adjacent the opposite end of the handle, without involving swinging movement of the handle.

I claim:

1. In a tool construction, a handle member, a tool head pivotally mounted on said handle member, a link member pivotally mounted on said head and slidable longitudinally of said handle, a pawl pivotally mounted on one of said members and cooperating ratchet means on the other of said members to prevent sliding movement of said link relative to said handle selectively in either direction of movement, said pawl, when in position to hold said link against sliding movement in one direction, providing for free movement of said link in the opposite direction of movement.

2. In a tool construction, a handle member, a tool head pivoted to said handle and arranged to support tools removably thereon, a connecting member pivotally secured to said tool head and slidable on said handle to vary the angularity between said tool head and said handle, a pawl pivotally mounted on one of said members and cooperating ratchet means on the other of said members to support said connecting member against movement relative to said handle selectively in either direction of movement in any position thereof.

3. In a tool construction, a handle, tool heads pivotally mounted on said handle at opposite ends thereof, connecting members pivotally mounted on said heads and connected to each other, whereby said members having a single slidable connection with the handle at their point of connection, swinging movement of one tool head will procure corresponding swinging movement of the other tool head without movement of said handle, and means to prevent movement of said heads selectively in either direction, said means providing for free movement of said heads in the opposite direction.

CERTIFICATE OF CORRECTION.

Patent No. 1,924,023.

August 22, 1933.

AUGUST E. CARLBERG.

It is hereby certified that error appears in the printed specification of the above numbered patent requiring correction as follows: Page 2, line 138, claim 3, strike out the word "whereby" and insert the same before "swinging" in line 140; and that the said Letters Patent should be read with this correction there-in that the same may conform to the record of the case in the Patent Office.

Signed and sealed this 24th day of October, A. D. 1933.
